UNITED STATES PATENT OFFICE

CLIFTON BOWMAN, OF HAMPTON, VIRGINIA

VALVE GRINDER

Application filed December 7, 1931. Serial No. 579,607.

This invention relates to valve grinders, and its general object is to provide a valve grinder that is capable of grinding several valves of an internal combustion engine simultaneously, or a single valve can be ground if desired.

A further object of the invention is to provide a valve grinder of the character set forth, that is simple in construction, inexpensive to manufacture, and extremely efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view partly in section illustrating the valve grinder which forms the subject matter of the present invention in use and arranged for grinding two valve simultaneously.

Figure 2 is a similar view but arranged for grinding a single valve.

Figure 3 is a sectional view taken approximately on line 3—3 of Figure 1, looking in the direction of the arrows.

Figure 4 is a sectional view taken approximately on line 4—4 of Figure 1, looking in the direction of the arrows.

Figure 5 is a sectional view taken approximately on line 5—5 of Figure 1, looking in the direction of the arrows.

Referring to the drawings in detail, the reference numeral 1 indicates a housing which forms the body of my tool and this housing is substantially oval shape in longitudinal cross section as best shown in Figure 4. The top of the housing is indicated by the reference numeral 2 and detachably associated therewith, with screw bolts for securing the top in place. Formed with and rising from the top is a substantially bail shape handle 3, while formed with and depending from the bottom of the housing is a

sleeve 4 which has its bore extending into the housing as clearly shown in Figure 1, and the portion of the bore that is arranged in the bottom is enlarged and threaded to threadedly receive a collar 5 that forms a part of a ball race for the balls 6 of a bearing, the latter being provided for a socket member 7 which has the other part of the ball race formed therewith and rising therefrom is a stud 8 arranged in the housing and has secured thereto a gear 9 for a purpose which will be presently apparent. Formed with the lower portion of the socket member 7 is a gear 10 that is adapted to mesh with gears 11, there being one gear 11 fixed to each of the spindles 12 which are identical in construction and have their upper ends mounted for rotation in bearing openings arranged at the bottom and top of the housing as best shown in Figure 1.

Each of the spindles is provided with an annular groove arranged adjacent its upper end for the purpose of accommodating a spring ring lock washer 13 that holds the spindles within the housing, and by this construction it will be apparent that the spindles can be removed from the housing upon removing the spring ring lock washers from their grooves.

The lower ends of the spindles are reduced and slotted longitudinally to provide spaced arms 14 between which are pivoted bit members 15 that have formed therewith spaced parallel lugs 16 adapted to be received in the openings in the heads of the valve as shown in Figure 1, and the bit members 15 also have extending from one of their ends a tongue 17 for use with valve heads that are provided with slots, with the result it will be noted that my tool is capable of operation upon valves of different types.

Formed with and depending from the socket member 7 and extending below the gear 10 thereof is a split collar providing what may be termed spring fingers 18 for the purpose of frictionally engaging one of the spindles 12 when it is desired to use the tool for grinding a single valve, and in this instance the spindle is inserted within the socket member as clearly shown in Figure 2.

In order to rotate the spindles when they are used in unison as shown in Figure 1, or when only one spindle is used as shown in Figure 2, I provide a rack bar 19 that is mounted for slidable movement horizontally through the housing which has formed therewith hollow guide arms 20 for the rack bar and these guide arms extend from diametrically opposite sides of the housing as best shown in Figure 4. The rack bar has secured to one end thereof a handle 21, and it will be obvious that upon reciprocating the rack bar which has its teeth arranged in mesh with the gear 9, that the gears 11 are rotated through the instrumentality of the gear 10 and the socket member 7, as the latter has the gear 9 secured to the stud 8 thereof.

From the above description and disclosure of the drawings, it will be obvious that I have provided a tool for grinding, reseating and polishing the valves of an internal combustion engine in an easy and expeditious manner with very little effort, and one valve or several may be operated upon simultaneously.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A valve tool of the character described comprising a housing, a top detachably secured to said housing, a handle secured to and rising from said top, spindles detachably mounted for rotation in said housing, bit members pivotally secured to the lower ends of said spindles, means for rotating the spindles simultaneously and means included in the rotating means for receiving either one of said spindles upon its removal from said housing, whereby either one of the spindles may be rotated singly.

2. A valve grinding tool comprising a housing, a handle rising from the top of said housing, a sleeve depending from the bottom thereof and having its bore extending into said housing, a socket member mounted for rotation in said sleeve, a stud formed with said socket member and arranged in said housing, a gear secured to said stud, spindles having one of their ends rotatably mounted in said housing and being detachable therefrom, bit members pivotally secured to the lower ends of said spindles, means for rotating the spindles from the socket member, and means for rotating the gear to rotate the socket member.

3. A valve grinding tool comprising a housing, a detachable top for said housing, a handle formed with and rising from said top, a sleeve formed with and depending

from the bottom of said housing, a socket member mounted for rotation in said sleeve, a stud formed with the socket member and arranged in said housing, spindles mounted for rotation in the top and bottom and detachably associated therewith whereby either one of said spindles may be inserted in the socket member, means for securing either spindle within the socket member, bit members for said spindles, a gear secured to the stud, means for rotating the gear to rotate the socket member, and means for rotating the spindles from the socket member when the spindles are secured to the top and bottom.

4. A valve grinding tool comprising a housing, a handle secured to said housing and rising therefrom, a sleeve depending from the bottom of said housing, a socket member mounted for rotation in said sleeve, a stud formed with the socket member and arranged in said housing, a gear secured to said stud, a rack bar mounted for reciprocation through said housing for rotating said socket member through the medium of said gear, spindles having their upper ends mounted for rotation in said housing, bit members pivotally secured to the lower ends of said spindles, means for simultaneously rotating said spindles from the socket member and either one of said spindles being adapted to be detachably secured in the socket member for individual rotation.

5. A valve grinding tool comprising a housing, a handle secured to said housing, means mounted for rotation and carried by said housing, means for rotating the rotatably mounted means and being mounted for reciprocation through said housing, spindles detachably secured in said housing and depending therefrom, means included in the rotating means for detachably receiving either of said spindles, whereby either spindle may be rotated singly, means for simultaneously rotating the spindles from the rotating means when the latter are secured to said housing, and bit members pivotally secured to said spindles and including means for association with various types of valve heads.

6. A valve grinding tool of the character described comprising a housing, a handle secured to said housing, a pair of spindles having their upper ends detachably mounted in said housing for rotation, means for rotating said spindles and carried by said housing, means including the rotating means to detachably receive either one of said spindles when the latter are moved from said housing, bit members pivotally secured to said spindles, lugs included in said bit members, and a tongue formed with said bit members.

7. A valve grinding tool comprising a housing, a handle secured to said housing, spindles detachably secured in said housing

and mounted for rotation therein, means for rotating said spindles simultaneously, means included in said rotating means for detachably receiving either one of said spindles,
5 bit members secured to said spindles, guide arms formed with said housing and extending from diametrically opposite sides thereof, and a rack bar mounted for reciprocation through said housing and guide arms
10 to rotate the rotating means.

In testimony whereof I affix my signature.

CLIFTON BOWMAN.
